UNITED STATES PATENT OFFICE.

CHARLES H. SEARS, OF BELLINGHAM, WASHINGTON.

BOX-FILLER.

1,246,334.

Specification of Letters Patent. Patented Nov. 13, 1917.

Application filed September 25, 1916. Serial No. 121,996.

To all whom it may concern:

Be it known that I, CHARLES H. SEARS, a citizen of the United States, and a resident of Bellingham, in the county of Whatcom and 5 State of Washington, have invented certain new and useful improvements in Box-Fillers, of which the following is a specification.

My invention relates to improvements in box fillers of the kind used to place cans of 10 fish, or other canned food products, in shipping boxes and the object of my invention is to provide a semi-automatic device which is simple and rapid in operation and simple of construction.

15 My invention is illustrated in the accompanying two sheets of drawings in which Figure 1 is a side elevation of my device, Fig. 2 is a front elevation of Fig. 1, Fig. 3 is a separated, rearward elevation view of 20 the can tray, Fig. 4 is a plan view of Fig. 1, Fig. 5 is a side elevation of the upper end of the empty-box magazine, and Fig. 6 is a diagonal plan view of the lower end of said magazine. Similar characters refer 25 to similar parts in the several views. Certain parts are broken away in order to show others hidden thereby.

More particularly: The legs 2, 2, etc. of the frame are fastened together by bars 2^a, 2^b, 2^c, etc. Cradle 9 is revolvable through an arc on gudgeons 9^a, 9^b which are mounted for revolution in bars 2^a, 2^c. When said cradle is in its filling position, shown in full lines, it bears on frame bar 2^c and when 30 turned to its dumping position, shown in dotted lines at 9', Fig. 1, it bears on frame bar 2^a. The right-hand end of cradle 9 is provided with stop bar 9^b. Box magazine 4 has rear side 4^b and front side 4^a, 4^c. The 35 lower end of said magazine terminates in foot board 4^c which is in a plane parallel with and somewhat above the bottom of cradle 9 when the same is in its filling position. Side 4^b of the box magazine serves 40 as a stop for the left-hand side of foot board 4^c. A box stop 5 on magazine side 4^b is in the path of movement of the empty boxes 45 d, e, f, etc., as they proceed down the magazine. Beginning at a point up magazine 4 a distance above stop 5 somewhat greater than the width of an empty box said magazine is widened from that point downward by a distance somewhat greater than the thickness of stop 5. Drag 6 hinged to magazine 4 near its upper end, Fig. 5, bears on 50 top of empty boxes k, m, d, e, etc., as they proceed down said magazine. Said drag terminates below at a point somewhat more than a box width above stop 5, Fig. 6. Drag 6 presses downward by its own weight on top of said empty boxes as they pass underneath and thereby retards their movement as they slide down the magazine. In Fig. 6 the action of the empty boxes on reaching stop 5 is clearly shown. Here the lower left-hand corner of box f is bearing on stop 5 while its right-hand upper corner is bearing against side 4^a. Because of the increased width of the magazine at this place said right-hand upper box corner is at a lower 55 level than said left-hand upper corner and box f is retained diagonally in said magazine with box e bearing on its left-hand upper corner. To release box f from its full line position in Fig. 6 upward pressure is applied under its right-hand lower corner when, because of the friction between said upper corner and box e, said box moves to its dotted position at f' where it is clear of stop 5 and can pass down the magazine, 60 when the pressure beneath it is removed, and occupy the position g on foot board 4^c, shown only in Fig. 1. Shelf 7^b, having left-hand stop 7^c and front stops 7^e, 7^d is fixed above and in front of cradle 9 parallel with the 65 same. Can tray 8 having front 8^a with handles 8^b, 8^c, is suited to sit on shelf 7^b as shown. Lever 11 is mounted for partial revolution on brackets 11^c which are fastened to the bottom of shelf 7^b. Lug 11^a projects 70 upward from lever 11 and enters hole 7^g in said shelf. Can stop 11^b projects upward from the right-hand end of lever 11 in front of the right-hand end of said shelf. Counterweight 11^d is attached to the left-hand 75 end of said lever. The weight of tray 8 bearing on lug 11^a is sufficient to overcome said counterweight and retain lever 11 and can stop 11^b in their full line positions where the top of said stop is nearly flush 80 with the top of shelf 7^b. But when tray 8 is lifted from said shelf lug 11^a passes upward through hole 7^g and can stop 11^b passes upward to its dotted position in Fig. 2. The lower end of can rollway 10, which 85 does not appear in Fig. 1, terminates near and above the right-hand end of shelf 7^b. Can stop 11^b can pass between the neighboring ends of said shelf and said rollway. 90

My device operates as follows: Filled cans 110 a, a, etc. roll down chute 10 from a preceding apparatus, not shown, and into tray

8 until it is filled where they are shown as cans *b*, *b*, etc. The length of tray 8 is suited to hold as many of said cans as the length of box *h*. An operator is stationed in front 5 of shelf 7^b. With his left hand he presses upward under box *f*, as described, which falling to foot board 4^c, is drawn by said hand on to cradle 9 to position *h*. Then he grasps handles 8^b, 8^b in each hand and lifts 10 tray 8 with cans *b*, *b*, etc. and properly places said cans in box *h*. The upturned ends of the bottom of tray 8 prevent the cans from rolling off of the same while being carried to box *h*. As tray 8 is raised from 15 shelf 7^b can stop 11^b rises in front of forward can *a* and prevents the same from leaving chute 10. When cans *b*, *b*, etc. are placed in box *h* tray 8 is replaced on shelf 7^b, causing lug 11^a to move downward and 20 lever 11 with can stop 11^b to again occupy their full line positions where said can stop is out of the way of cans *a*, *a*, etc. and said cans roll into tray 8 until the same is again filled. The operator places this tray full of 25 cans in box *h* as before and repeats the described operations until box *h* is properly filled with said cans. Said operator then places his right hand on top of box *h* and shoves forward. This force rocks cradle 9 30 to its dotted position at 9' and carries box *h* to its dotted position at *h*'. Pressure being then removed from box *h* it slides down chute 3 to position *i* where it is ready to receive its cover. Cradle 9 is now returned to 35 its full-line position by hand, an empty box placed on the same as before and filled with cans as already described.

I have found this device as described very 40 satisfactory in practical use. However there are doubtless changes in detail which could be used to advantage without evading my claims which are,

1. In a box filler, in combination, a fixed 45 can rollway, a removable can tray, a fixed can-tray shelf, an oscillatable can stop fulcrumed on said shelf and having a part occupying said shelf depressible by said can tray and another part barring the exit from said rollway when said depressible part occupies 50 said shelf but vacating said exit when said former part is depressed.

2. In a box filler in combination, a can rollway, a fixed can-tray shelf in proximity to the exit end of said rollway having a hole therethrough, a counter-weighted lever under said shelf, a lug on said lever in said hole in said shelf, a can stop on the unweighted end of said lever enterable between the proximate ends of said rollway and said shelf and a removable can tray on 60 said shelf bearing on said lug.

3. In a box filler in combination, a box magazine having a foot board, a rockable box cradle in proximity to said foot board, a can-tray shelf near said cradle, and a can 65 rollway the exit end of which is proximate to said shelf.

4. In a box filler in combination, a box magazine having a foot board, a rockable box cradle in proximity to said foot board 70 when said cradle is in its filling position, and a box chute in proximity to said cradle when it is in its dumping position.

5. In a box filler in combination, a rockable box cradle, a box magazine having a 75 widened part and a foot board in proximity to said cradle, and a box stop attached to said magazine at said widened part of the same.

6. In a box filler in combination, a rockable box cradle, a box magazine having a widened part and a foot board in proximity to said cradle, a box stop attached to said magazine at said widened part of the same, and a box drag hingedly attached to said 85 magazine.

7. In a box filler in combination, a rockable box cradle, a box magazine having a foot board in proximity to said cradle, a can-tray support near said cradle, a can 90 rollway in proximity to said can-tray support, a removable can tray on said support, and means to close the exit from said rollway operated by the removal of said tray from said support.

Signed at Bellingham, in the county of Whatcom and State of Washington, this 19th day of September, A. D. 1916.

CHARLES H. SEARS.
